UNITED STATES PATENT OFFICE.

CLARENCE WARNER, OF DAYTON, OHIO, ASSIGNOR TO DELCO-LIGHT COMPANY, OF DAYTON, OHIO, A CORPORATION OF DELAWARE.

PUMPING APPARATUS.

Application filed October 3, 1923. Serial No. 666,282.

To all whom it may concern:

Be it known that I, CLARENCE WARNER, a citizen of the United States of America, residing at Dayton, county of Montgomery, State of Ohio, have invented certain new and useful Improvements in Pumping Apparatus, of which the following is a full, clear, and exact description.

This invention relates to pumping apparatus, and has among its objects the provision of a pump driving mechanism that will be simple and compact and may be readily disassembled for repairs or replacement of parts.

Another object of the present invention is to provide for the lubrication of the mechanism with the minimum liability of mixing the lubricant with the fluid being pumped.

Other and further objects and advantages of the present invention will be apparent from the following description, reference being had to the accompanying drawing, wherein a preferred embodiment of one form of the present invention is clearly shown.

In the drawings:

Fig. 1 is a vertical sectional view of a pump driving mechanism embodying the present invention.

Fig. 2 is a sectional view taken on the line 2—2 of Fig. 1.

Fig. 3 is a view in elevation of the pump driving mechanism, looking in the direction of the arrow A in Fig. 1, a portion of the motor being broken away.

Fig. 4 is a diagrammatic view, looking in the direction of the arrow B in Fig. 1, showing various positions of the driving mechanism.

Fig. 5 is a fragmentary sectional view taken on the line 5—5 of Fig. 1.

Referring to the drawings, a gear housing 20 is secured to a base 21 by bolts 22. Housing 20 is provided with an annular flange 23 providing a relatively wide bearing surface. An end cover 24 provides a closure for an opening 25 in gear housing 20, and is secured thereto by bolts 26. The cover 24 also provides a bearing 27. Cover 28 which encloses bearing 27, is secured to cover 24 by bolts 29. Thus the housing 20 and cover 24 constitute a lubricant chamber 30.

A casing 35 which is secured to the housing 20 by bolts 36, is provided with an opening 37. This casing 35 also provides a lubricant chamber 38, having communication with lubricant chamber 30 through passage 39 and through the interior of flange 23. A casing 40 which is secured to the wall 41 of casing 35 by bolts 42 and nuts 43, provides for the passage therethrough of a reciprocating pump rod 45. A removable cover 46, secured to casing 40 and casing 35 by screws 47, provides a closure for the upper end of pump rod 45 and a connecting arm 48 which fits over the threaded end of pump rod 45. Nuts 49 and 50 permit of adjustment of the connecting arm 48 with respect to the pump rod 45. Arm 48 extends downwardly through the opening 37 in casing 35.

An electric motor 50 is attached to one end of the gear casing 20 and is provided with a motor shaft 51 which extends through casing 20, and is journalled in bearings (not shown) carried by casing 20. A flywheel 52 is suitably secured to motor shaft 51 at the opposite end of casing 20, and cover 53, secured to casing 20 by bolts 54, provides a closure for the flywheel 52. A worm 55 is provided on motor shaft 51 substantially centrally of casing 20.

An internal gear 60 is secured to the inner surface of casing 20 by bolts 61 and is arranged concentric with the opening provided by annular flange 23. Reduced portion 62 of gear 60 is adapted to fit within the recessed portion 63 of casing 20, so that the gear 60 may be easily located in proper position with respect to the opening provided by annular flange 23. A rotatable member 65, provided with a disc flange 66, is journalled in the relatively wide bearing 67 provided by an annular flange 23. Rotatable member 65 is secured to a shaft 70 as an axis by key 71. Shaft 70 is provided with a shoulder 72 which engages a recess 73 in member 65. A sleeve or journal member 74 having a reduced portion 75, is also secured to shaft 70 by key 71. Bearing 100 sleeve 76 fits loosely over the reduced portion 75 of sleeve 74, and is threaded as at 77 for engagement with the tapped outer end of bearing 27. A nut 78 also engages the threaded portion 77 to prevent accidental 105 turning of sleeve 76. A washer 79, and a

nut 80 engaging the threaded end of shaft 70 limit endwise movement of sleeve 74 and shaft 70 with respect to the sleeve 76.

Member 65 provides bearings 80 and 81 eccentric with respect to shaft 70 and which are spaced apart by opening 82. A crank shaft 83, having a crank arm 84, is journalled in bearings 80 and 81, and is held in position by washer 85 and nut 86 engaging the threaded end of crank shaft 83. A gear 90, the diameter of which is equal to the radius of internal gear 60, is secured to shaft 83 between bearings 80 and 81 by a key 91 and meshes with stationary internal gear 60. A worm gear 92, which is formed in the periphery of disc 66 cooperates with worm 55 on motor shaft 51. Play or back lash between gears 92 and 51 can be removed by screwing the sleeve 76 with respect to the bearing 27. Sleeve 76 is provided with notches 76^a to receive a suitable wrench for turning the sleeve. The adjusted position of sleeve 76 is maintained by lock nut 78.

A crank pin 95 is carried by crank arm 84, and is adapted, upon rotation of crank shaft 83 and shaft 70, as before described, to be reciprocated within the lubricant chamber 38. Crank pin 95 is connected with connecting arm 48 by a universal connection shown in Fig. 5, the arm 48 being notched at its lower end at 96 and receiving a member 97 which is pivotally held in notch 96 by a bolt 98. Member 97 supports a bearing 99 which receives the crank pin 95. A cotter pin 100 and a washer 101 hold the member 97 and bearing 99 in position on the crank pin 95.

Fig. 4 shows diagrammatically two positions of the gearing for transmitting straight line motion to the pump rod 45 and arm 48. In this figure, the circle 60 represents the gear 60 and the circle 90 the gear 90 which meshes with the gear 60. The full line position of circle 90 represents the lowest vertical position of the gear 90 as it rolls within the internal gear 60. The rotatable member 65 is represented as an arm 65 in Fig. 4 which rotates about the point 70 representing the shaft 70, and carries with it the crank shaft 83 represented by circle 83 in Fig. 4. Line 84 represents the crank 84 and connects the crank shaft 83 with the crank pin represented by circle 95 in Fig. 4. Since the pitch diameter of gear 90 is equal to the pitch radius of gear 60, it follows that the path of movement of any point on the pitch circumference of gear 90 will be a straight line as the gear 90 rolls within the gear 60. Since the length of crank 84 is equal to the pitch radius of gear 90, it follows that the crank pin 95 will move in a straight line. As shown in Fig. 4, the axis of pin 95 coincides with the point of contact of the pitch circles of gears 90 and 60 when gear 90 is in the lowest

position. Therefore the path of movement of the axis of crank pin 95 will be in a vertical line passing through the axis of gear 60 and shaft 70. Since the crank pin 95 moves in a straight line as its crank shaft 83 moves in an orbital path indicated by the dotted circle 183 in Fig. 4, it follows that the arm 48 connecting the crank pin 95 with the pump rod 45 will have simply straight line motion and will not be oscillated. Therefore no bearing requiring lubrication is necessary in the connection between the connecting arm 48 and the pump rod 45. It follows therefore that the bearings requiring lubrication can be all located within relatively limited boundaries, thereby facilitating the lubrication of such bearings and permitting the use of simple means for preventing the escape of lubricating oil to the pump rod and to the well through which the pump rod extends.

The mechanism which imparts to the crank pin 95 a straight line motion from the rotating shaft 70, is of such a nature as to cause a force to be applied to the crank pin in either direction of its motion which is relatively great at the end of its travel up or down as compared with intermediate portions of its travel. In other words, a toggle action is produced upon the crank pin 95. This action is shown diagrammatically in Fig. 4. Assume that the direction of rotation of the rotatable member 65 is clockwise, as indicated by the arrow C in Fig. 4. As the crank pin 95 moves vertically upwardly, the rotatable member indicated by the line 65 in Fig. 4, will move into a position such as 65^a, thereby producing orbital movement of the crank shaft 83 in the orbit 183. The gear 90 will move to the position 90^a and the crank arm 84 will take the position 84^a causing the crank pin 95 to move to the position 95^a. The members 65 and 84 are in effect toggle links. The mechanism causes the link 65 to rotate about the axis 70 thereby causing the toggle link 84 to rotate about the axis 83. As already explained, the movement of the crank pin 95 at the end of link 84 is confined to straight line movement. Since the distance moved by the point 83 to point 83^a is much greater than the distance moved by pin 95 to point 95^a, it follows that the force applied at the pin 95 is greater than the force applied at the point 83 at the beginning of upward movement of pin 95. This action is advantageous in pumping apparatus since relatively great force is required at the beginning of each stroke of the pump rod in order to overcome inertia, weight of the moving parts and the water lifted by the pump.

It will be apparent that the lower edges of the bearing 99, which is reciprocated in the lubricant chamber 38, is below the level of the opening 37 at all times, so that when

dipped into the lubricant and moved upwardly to its highest level, the lubricant will be retained within the lubricant chamber 38, and will not come in contact with pump 5 rod 45 and thus get down into the well. As the member 65 is rotated, the bearings 80 and 81 will dip into the lubricant and thus lubricate the crank shaft 83. Gear 90 will be lubricated by lubricant entering the cored 10 opening 82. The lower edge of bearing 67 is submerged in lubricant and the worm gear 93 carries lubricant to the worm 51.

The casings 40 and 41 may be removed as a unit from the gear casing 20 by removing the bolts 36 or casing 40 may be removed separately by loosening nuts 43. To remove the gearing from the gear housing 20, the cotter pin 100 and washer 101 are removed, and the crank arm 84 is turned to a 20 position so that it will clear the flanged portion 23 of housing 20. Then the screws 26 are removed. It is then possible to remove through opening 25 of gear housing 20, the cover 24, the shaft 70, member 65 and 25 other parts carried thereby, all in assembled relation.

While the form of mechanism herein shown and described constitutes a preferred embodiment of one form of the invention, it is to be understood that other forms might be adopted and various changes and alterations made in the shape, size, and proportion of the elements therein without departing from the spirit and scope of the invention.

What is claimed is as follows:

1. A pump operating device comprising a hollow frame enclosing various of the parts thereof and having a vertically extending 40 pump rod passage open at its upper end, a lubricant containing chamber provided with an opening in its top located adjacent the open upper end of said passage, a vertically arranged wall separating said chamber and passage from one another, and an internal annular bearing flange; a reciprocating pump rod extending along said passage; a reciprocating member the upper end of which is operatively connected with said pump rod, and the lower end of which is arranged to move through the opening aforesaid in the top wall of said lubricant containing chamber; a rotatable operating member housed within said hollow frame and supported in 45 said annular bearing flange; mechanism carried by said rotatable operating member and operatively connected with said reciprocating member to thereby impart reciprocatory movement to said pump rod; and a motor operatively connected with said rotatable operating member to drive the same.

2. A pump operating device comprising a hollow frame enclosing various of the parts thereof and having a vertically extending 55 pump rod passage open at its upper end ar-

ranged at one end thereof, and the other end of which frame is provided with an opening, a lubricant containing chamber provided with an opening in its top located adjacent the open upper end of said passage, a vertically arranged wall separating said chamber and passage from one another, and an internal annular bearing flange; a reciprocating pump rod extending along said passage; a reciprocating member the upper 70 end of which is operatively connected with said pump rod, and the lower end of which is arranged to move through the opening aforesaid in the top wall of said lubricant containing chamber; a rotatable operating member housed within said frame and one end of which is supported in said annular bearing flange; a cover for closing the open end of said frame, and which cover is provided with a bearing wherein the other end of said rotatable operating member is supported; a gear carried by said rotatable operating member; means carried by said rotatable operating member and operatively connected with said reciprocating member to thereby impart reciprocatory movement to said pump rod; and a motor operatively connected with said gear to drive the same.

3. In a pump operating device of the class described, a rotatable operating member having a cylindrical journal at one end whereby it may be rotatably supported in an annular bearing flange, and a gear at its other end whereby it may be driven from a suitable motor; a crank shaft arranged eccentric to and parallel with the axis of rotation of said operating member, and which shaft is rotatably supported in spaced bearings carried by said journal and said gear; a gear carried by said crank shaft and located between said bearings; a crank carried by said crank shaft and located adjacent said journal, and which crank is operatively connected with a pump rod to impart reciprocatory movement thereto; and an annular stationary gear arranged concentric to said journal, and having internal teeth with which the teeth of the second mentioned gear aforesaid mesh.

4. A pump operating device comprising a hollow frame enclosing various of the parts thereof and having a vertically extending pump rod passage arranged at one end thereof, and the other end of which frame is provided with an opening, a lubricant containing chamber within said frame, a vertically arranged wall separating said chamber and passage from one another, and an internal annular bearing flange; a reciprocating pump rod extending along said 115 passage; a reciprocating member operatively connected with said pump rod to impart reciprocatory movement thereto; a rotatable operating member housed within said frame and one end of which is supported in said 120

125

130

annular bearing flange; a cover for closing the open end of said frame, and which cover is provided with a bearing wherein the other end of said rotatable operating member is supported; a gear carried by said rotatable operating member; means carried by said rotatable operating member and operatively connected with said reciprocating member to

thereby impart reciprocatory movement thereto and to said pump rod; and a motor 10 operatively connected with said gear to drive the same.

In testimony whereof I hereto affix my signature.

CLARENCE WARNER.
